Application November 17, 1938, Serial No. 240,885

14 Claims. (Cl. 200—152)

This invention relates to switches, and more particularly is directed to mercury switches of the metallic envelope type adapted to be operated by longitudinal tilting of the switch to flow a body of mercury into and out of contact with a second body of mercury retained against an electrode.

More specifically, the present invention is directed to certain detailed improvements in switches of the type shown generally in my co-pending application, Serial No. 745,862, filed September 28, 1934.

The present invention is directed particularly to a switch assembly comprising a cup-shaped electrode formed of metal having an enlarged open end in which is seated a ceramic or refractory insert which centers and supports an electrode and is sealed in position within the switch by means of suitable resilient gasket means.

In such switches there is considerable difficulty in providing a tight seal, and also in providing a construction which will allow for the rapid distribution of heat generated within the sealed envelope due to the making and breaking arcs as the switch is tilted in opposite directions.

One of the main features of the present invention resides in a construction for insuring the retention of a body of mercury in contact with the secondary electrode and in a position so that a mercury to mercury contact is effected when the switch is tilted. This retained body of mercury is preferably so related to the secondary electrode as to have an appreciable surface contact therewith in order to reduce materially the resistance to the flow of current.

Still another feature of the present invention is the provision of a compression insulator designed with either a tapered or counterbored opening in the electrode shank. This is of distinct advantage in view of the spinning operations in sealing the envelope closed since with such a construction, the spinning operation, which produces a slightly radially inward thrust on the compression insulator, will not cause the insulator to crack or be damaged due to the fact that a slight clearance around the shank of the electrode is provided.

Still another feature of the invention is the provision of a switch in which the switch envelope is filled with either a liquid or a gas capable of producing a reducing atmosphere. This may, if desired, comprise a filling of hydrogen gas or a liquid filling of triethanolamine, diethanolamine, or any other anhydrous alkaline liquid. It is desirable that some such reducing atmosphere be provided within the switch envelope in order to

keep the metallic parts clean and bright, and also to act as a medium for preventing the formation of oxides on the surface of the mercury. In addition the liquid fill, as described above, has the characteristic of increasing the normal meniscus height of the mercury so that a greater surface contact is effected when the switch is tilted toward closed position. It also acts as an enveloping film over the moving mercury body and over the retained body of mercury, and serves as a floatation medium within which is suspended impurities which may be picked up from the mercury or from the walls of the envelope.

One great difficulty attendant upon the use of hydrogen in the metal envelope switch of this type is the fact that ordinary soft iron cannot confine hydrogen gas. The hydrogen apparently penetrates through the pores of the metal and escapes from within the switch envelope. This inability to retain the hydrogen in iron and similar ferrous bodies is a distinct problem, as otherwise, hydrogen would be a desirable reducing atmosphere within the switch envelope.

It is to be understood that there is a distinct difference between the use of an inert atmosphere and the use of a reducing atmosphere of this type. Obviously, with an inert atmosphere there is no tendency to keep the walls of the switch clean and bright or to prevent any possible oxidation within the envelope. On the other hand, with the reducing atmosphere, oxidation is positively prohibited, and the walls of the envelope are maintained in a highly polished condition.

In order to employ hydrogen in a sealed metal envelope switch of this type, I have found it necessary to provide an enclosure of metal impervious to hydrogen. For this reason I have found that a clad metal is best suited for a switch envelope if a hydrogen atmosphere is to be used therein. In a preferred form of the invention this comprises a metal envelope having an internal surface composed of steel of the type similar to SAE-1010, which has thereabout a coating of copper or a similar metal impervious to hydrogen. Preferably, copper is employed because of its low resistance to the passage of electrical current, thereby reducing the resistance through the switch. This copper layer may be of sufficient thickness to provide the proper strength of shell to resist internal pressures that may be developed, and can be used for preventing any possible escape of hydrogen through the relatively thin steel lining within the shell.

Also, I have found that pure iron does not unite with the mercury, nor does it even wet with mer-

cury in the manner that stainless steel is wetted when contacted by a body of mercury. This produces a certain resistance in the contact between the two metals. While nickel wets with mercury, it apparently has about the same resistance in contact therewith and repeated flashing of mercury in the presence of a nickel surface causes a stickiness of the mercury, showing a certain chemical reaction being produced between the mercury and the nickel.

I have found that hot rolled sheet formed of an iron alloy, better known as SAE-1010, draws into body shapes for use in mercury switches much better than iron. Also, during the drawing operations, this metal polishes in such a manner that the contact resistance, as the metal and mercury lie in contact, is appreciably reduced. An examination of the contact surface of this metal shows that the entire surface is composed of closely spaced minute points which have been wetted with the mercury. This does not produce an amalgamation, nor does it produce a surface wetting such as produced when a nickel steel is employed. The surface apparently looks clean, but the plurality of minute points are wetted with the mercury and a much closer affinity between the mercury and the hot rolled sheet metal is produced which results in a reduced contact resistance between the two; such as to provide a much cooler operating switch due to the reduction of resistance therethrough, and the consequent reduction in heat generated by such current. Preferably the composite envelope formed of the SAE-1010 lining and the copper coating is so designed that approximately 5 to 10 percent of the wall thickness is composed of the hot rolled sheet iron, while the remaining 90 to 95 percent of the wall is composed of copper, which greatly reduces the resistance through the switch.

In switches of the type where speed of operation is not essential, such as used on calibrated instruments, control devices and the like, where the switch cuts in or cuts out at certain predetermined points. I have found that a certain relationship exists between the operating angle of the switch and the length of the body of mercury which is retained against the electrode. The length of the mercury is defined as the distance between the sharp cutting edge on the ceramic insert and the planar face of the electrode. Almost a direct functional relationship exists between this length and the operating angle of the switch throughout the range between a maximum of $\frac{3}{2}$ of an inch and a minimum of about $\frac{3}{4}$ of an inch. The operating angle within this range decreases substantially directly with the decrease in the length of the retained body.

Another feature of the present switch is the design of an electrode and its shank in such manner as to form adequate heat dissipation from the face of the electrode to the external part of the switch. This may be accomplished by providing finned ribs or other heat dissipating means for increasing the rate of heat dissipation from the electrode face.

Still another feature of the present invention is the provision of an auxiliary ceramic of the "Alundum" type for forming the sharp cutting edge over which contact is made and broken. This is a highly thermally refractive material which will not be etched or eroded under repeated high tension arcs.

Other objects and advantages of the present invention will be more apparent from the fol-

lowing detailed description which, taken in conjunction with the accompanying drawings, will disclose to those skilled in the art the particular construction and operation of a preferred form of the present invention.

5

In the drawings:

Figure 1 is a sectional view through one form of switch embodying the present invention;

Figure 2 is a corresponding sectional view of a modified form of switch;

Figure 3 shows the use of an auxiliary insert to provide the sharp cutting edge over which contact is made and broken in the switch;

Figure 4 shows one form of compression insulator that may be employed;

Figure 5 shows a modification of this form;

Figure 6 is a sectional view through a switch with a modified electrode construction;

Figure 7 is a sectional view through another form of electrode;

Figure 8 is a sectional view through a still further modified form of electrode; and

Figures 9 and 10 are sectional views of other modified electrodes.

Considering now in detail the structure shown in Figure 1, this comprises a metallic envelope 5 having a radially directed shoulder portion 6 terminating in an enlarged end portion 7. The envelope 5 is preferably formed of hot rolled strip such as SAE-1010 by a drawing operation which, due to the characteristics of the metal, provides a relatively polished surface on the interior thereof. The closed end of the envelope is tapped as indicated at 8 to receive a tapered fill plug, which will be described in detail hereinafter.

Disposed within the enlarged end 7 of the envelope is a ceramic insert 9 which may be formed of "Isolantite" or a similar ceramic material, and which is provided with a radially inwardly directed flange portion 10 having the rounded defining edge 11. The flange 10 forms with the body of the insert 9 a shouldered portion against which electrode 12 is seated. The electrode 12 preferably has a cup-shaped face 13, the flanged edge 14 thereof abutting against the radial surface defining the flange 10 of the insert. The shank 11 of the electrode extends outwardly from the end of the envelope and is suitably threaded as will be described in detail hereinafter.

It will be noted that the axial length of the electrode 12 is such that the rear face thereof lies substantially coplanar with the outer end of the insert 9. Disposed against these surfaces and sealing the annular crack therebetween is a gasket member 15 which may be formed of synthetic rubber, such as "Neoprene" or the like.

The gasket 15 is adapted to be axially compressed by means of a compression washer 16, preferably formed of a ceramic material and having an axially directed reduced portion 17 fitting about the shank 11 of the electrode. Upon the outer portion of the ceramic compression washer 16 is a retaining ring 18 formed of metal and having an external diameter substantially identical with the internal diameter of the enlarged portion 7 of the shell 5. When the parts have been positioned as shown in Figure 1, the extending edge of the enlarged portion 7 of the shell is spun over as indicated at 19, the gasket 15 being maintained under compression in a manner such as described in detail in my co-pending application, Serial No. 211,420, filed June 2, 1938. Threaded on the shank 11 of the electrode is a washer 20 and a nut 21 whereby a suit-

70

75

able terminal conductor may be connected thereto.

It will be noted that by reason of the cup shape of the electrode face an annular space or groove is provided between the shoulder formed by the flange 10 and the face 13 of the electrode. Within this groove is disposed a body of mercury 22, the groove being of a width such that the body is retained permanently therein as described in my copending application, Serial No. 53,146, filed December 6, 1935. Also, a second body of mercury 23 is disposed in the main body portion of the shell 5, this mercury being adapted to move up the surface of the insert bore to contact with the retained body portion 22 when the switch is tilted toward circuit closing position. Disposed over the mercury is a liquid film, indicated at 24, which may comprise any anhydrous alkaline liquid such as triethanolamine, or a liquid of this class which, when vaporized, will produce a reducing atmosphere. The liquid film serves to prevent oxidation of the mercury and also floats the impurities which may remain in the envelope so that fresh clean mercury is employed for the contact at all times.

In the assembly of the switch, the parts disposed within the enlarged body portion 7 are placed in position and then maintained under a suitable pressure, while the spun-over edge 19 is rolled into position to lock the parts against displacement. This compresses the gasket both axially and radially forming a positive seal about the electrode shank and also within the enlarged portion 7 of the shell. With the parts thus placed in position, the interior of the envelope is evacuated through the opening 8 and the mercury and the liquid fill are introduced therein. With the envelope still in evacuated condition the interior thereof is sealed by means of a tapered fill plug 25 threaded into the tapered opening 8 and then further sealed by means of a globule of solder 26 or the like. This provides a positive seal for the interior of the envelope and prevents the admission of gas or moisture thereto. It will be noted that with this construction the retained body of mercury 22 has a substantial surface contact with the face 13 of the electrode 12, which reduces to a considerable extent the resistance to flow of current from the retained body into the electrode.

By using hot rolled strip of the type specified I am able to obtain a greater contact between the mercury and the metal wall of the envelope due, I believe, to the fact that the surface of the metal forms an infinite number of very fine points which are wetted by the mercury in the same manner as nickel steel is wetted, and which thus decrease the contact resistance between the mercury and the metal. This also reduces the electrical resistance through the switch, resulting in a cooler operating switch regardless of the speed of operation thereof. The present switch may also be operated by rapid axial reciprocating movement which drives the shoulder of the insert bore under the body of mercury 23, and due to the inertia of the body of mercury, causes the making or breaking of contact over the shoulder.

Considering now Figure 2 of the drawings, in this embodiment of the invention the shell 30 of the switch is drawn from what might be termed copper clad iron sheet. For example, the inner or lining surface of the shell is of a ferrous metal similar to that used in the shell 5 but this metal is clad with a coating or body of copper. The lining in the shell, which is of a ferrous metal,

is indicated at 32, while the enclosing body of copper or similar metal is indicated at 33. Inasmuch as hydrogen is to be employed in this particular switch construction, it is necessary that some material impervious to the passage of the hydrogen be used to prevent too great an absorption of the hydrogen by the ferrous metal. Copper is an excellent metal for this purpose and in addition has the advantage of high conductivity, thereby reducing the ohmic resistance through the switch.

Within the enlarged part of the envelope is the insert 34 corresponding to the insert 8 of Figure 1, except that in place of the rounded surface of the flange, it is provided with a frustoconical opening defined by the surface 35 and terminating in an abrupt acute angled edge defined by the radially extending wall 36. The insert 34 is counterbored to receive the electrode 12 which fits into the recess and is maintained against the radial surface 36 by means of the gasket 15. The remaining portions of the end construction of the switch are as described in connection with Figure 1, and corresponding reference numerals have been applied thereto. The spun-over edge of the shell 30 indicated at 37 locks these parts in compressed sealing position, and a retained body of mercury 22 and a movable body of mercury 23 are introduced in the switch in the same manner as previously described. However, after the switch envelope has been evacuated, hydrogen gas is forced thereinto through the opening 8, and preferably is maintained in the envelope under a pressure of 2 or 3 atmospheres. Inasmuch as the gasket 15 is impervious to hydrogen, an effective seal for the back face of the electrode 12 and the insert 34 is provided to prevent escape of hydrogen therethrough, while the cross sectional area of the shank 11 is relatively small, it is desirable that this shank be rendered impervious to the escape of hydrogen therethrough, and consequently the shank may be made of copper if so desired, which is also of advantage in that the conductivity therethrough is increased between the electrode 12 and the terminal connected beneath the washer 20 to the shank. With an acute angled cutting edge 38 as shown in Figure 2, a very positive operating switch is provided which will open and close the circuit therethrough at predetermined angular inclinations. This is what is termed "repeat performance"; that is, the switch will continue to close the circuit at a certain angle and to open the circuit at a certain angle. The included angle between the on and off position of the switch which is considered the operating angle of the switch, varies directly with the length of the retained body 22. For example, if the length of this body is 2 mm. the operating angle for the switch of the type shown is approximately $3\frac{1}{2}$ degrees. If the length of the retained body of mercury is increased to 3 mm., the operating angle increases to 4 degrees. It appears that with further increases in length of the retained body, the operating angle increases about $\frac{1}{2}$ a degree for each $\frac{1}{4}$ mm. increase in length in a very definite and regular manner until the length of the stable body reaches a point exceeding the stability point, which is about $\frac{7}{32}$ of an inch.

Considering now the form of the invention shown in Figure 3, the hot rolled strip which forms the shell 40 is provided with a frustoconical section 42 terminating in the enlarged cylindrical portion 43. The ceramic insert 60 is

Considering now the form of the invention shown in Figure 3, the hot rolled strip which forms the shell 40 is provided with a frustoconical section 42 terminating in the enlarged cylindrical portion 43. The ceramic insert 60 is

similarly provided with a frusto-conical external surface whereby this insert may seat directly against the corresponding portion of the shell. The insert 60 is also preferably provided with a rear face parallel with the rear face of the electrode 66, but provided with an axially recessed peripheral portion into which the flange portion 53 of the resilient gasket 54 is adapted to extend. This increases the leakage distance from the electrode to the interior of the shell 43, and also provides for an increased sealing effect of the gasket upon axial compression to prevent possible leakage of pressure outwardly past the insert or the electrode.

15 Preferably, a suitable compression insulator 51 is provided for producing axial compression of the gasket 54 when the edge of the shell 43, as indicated at 55, is spun over the retaining ring 56. It will be noted that the retaining ring 56 20 is of an internal diameter such as to extend radially inwardly of the external periphery of the electrode. The purpose of this construction is to prevent possible shear action due to internal pressure on the electrode from shearing the gasket or compression insulator, since the radial overhang prevents any possible shear stresses of this nature.

The interior of the envelope 40 may be provided with a liquid fill or with a gas fill, but in 30 the event that a reducing gas is employed, it is obvious that the shell 40 will be made of the two metals, as described in connection with Figure 2. The internal bore of the insert 60 is molded in such manner as to provide a frusto-conical recess 35 62, which has a shoulder portion 63 adapted to receive the annular wedge shaped refractory insert 64 held thereagainst by the flanged lip 65 of a cup-shaped electrode 66. The refractory insert 64 is preferably formed of a highly thermally 40 refractive material such as "Alundum," which has the characteristic of not being etched or eroded under high electric arcs, and which is capable of withstanding appreciably more abuse than the material 66 which may be of the type 45 known as "Isolantite." The retaining body of mercury 68 is disposed in the annular groove formed between the rear face of the insert 64 and the electrode cup formed by the flange 65 on the electrode face 66. It will be noted that 50 the insert 64 provides a cut-back so that when the switch is stood on end, only a small part of the mercury will escape from the annular groove, and consequently, when the switch is turned into its proper position there will be a sufficient 55 retained body collected in the lower arcuate portion of the groove to provide the proper mercury to mercury contact. It will also be noted that by this construction a very appreciable surface of the retained body is in contact with the electrode 60 66, thus decreasing the resistance therebetween.

In Figures 4 and 5 I have illustrated a modified form of compression insulator, the form shown in Figure 4 having the main body portion 80 provided with the extended axial shoulder 85 portion 82 which serves to space the electrode shank and insulate the same from the metallic retaining ring such as the ring 18 or 56. The member 80 is provided in this form of the invention with a tapered bore 83 which fits about the electrode shank and allows a slight amount of 70 movement of the compression insulator during the spinning operation to prevent buckling of the outer part of the insulator due to possible radial compression stresses thereon. This same result 75 can be produced by the compression insulator 85

shown in Figure 5 having the axially directed shoulder portion 86 and provided with a bore 87 having the shoulder portion 88 therein. With such a construction the shoulder portion 88 fits closely about the electrode shank for centering 5 the compression washer in position, while the enlarged portion of the bore 87 provides the necessary clearance to accommodate radial compression of the ceramic during the spinning operations. It is obvious that either of these forms 10 of the invention may be substituted in any of the switches, thus described, the form shown in Figure 4 being preferred in that the ceramic can be molded more easily for such a construction.

Considering now the form of the invention 15 shown in Figure 6, I have provided a cup-shaped envelope or shell 90 having the radial shoulder 92 on the enlarged open end portion 93. Seated against the shoulder 92 within the enlarged end 93 is a ceramic insert 94 having the frusto-conical 20 bore 95 therein which terminates in the sharp cutting edge 96 and the cut-back annular groove 97.

An electrode 98 is provided having the annular flange portion 99 disposed within and forming 25 the annular outer wall of the cut-back recess 97. The face of the electrode is spaced from the cutting edge 96 a distance such as to retain the body of mercury 100 therebetween in contact with the electrode and projecting above the cutting edge 30 102 in such manner as to provide for mercury to mercury making and breaking of contact with the movable contactor 102.

The electrode 98 is provided with a cylindrical extension 103 around which is disposed the resilient sealing gasket 104 adapted to be compressed by the annular compression washer 105 which has seated thereagainst the retaining ring 106 disposed beneath the spun over edge 107 of the shell. The compression washer 105 radially 40 encloses the extending portion of the cylindrical extension 103 of the electrode and serves to insulate the electrode from the retaining ring 106 and the end portion 93 of the shell 90 forming the other electrode. The electrode 98 within the cylindrical extension 103 is provided with an integral axially extending post construction 108 which is tapped at its outer end to receive the terminal screw 109 by which the conductor or 45 terminal lug 110 is secured to the electrode. With this construction the conduction of heat from within the switch envelope through the electrode is facilitated due to the annular cylindrical portion 103 forming a metallic path for the escape of this heat which provides for a much more rapid rate of heat dissipation than if the heat had to be dissipated through a rubber gasket and ceramic compression member. Also, with this construction there is provided an annular opening 112 about the post 108 insuring removal of 50 the heat from the metal through the circulation of air in this opening.

For switches which are operated many times per minute, such as sign flashing, advertising, or oscillating mechanisms, a construction of this type is desirable to prevent the building up of heat within the switch envelope and to insure a sufficient dissipation of heat to prevent the possibility of destroying or deteriorating the resilient sealing member 104 or the surface of the ceramic 70 insert 94 due to high temperatures being continually impressed thereon.

In Figures 7 to 10, inclusive, various forms of electrodes are disclosed which all have as their primary purpose a construction which will facilitate 75

state this dissipation of the heat. For example, in Figure 7 the electrode 113 is provided with the cup-shaped recess 114 within which the retained body of mercury is disposed and is provided with a rearwardly extending portion having the form of a cross section in a radial direction; that is, the rearwardly extending portion of the electrode 113 has the radially extending ribs 115 extending substantially at right angles to each other and 10 also directed axially rearwardly in planes passing through the axis of the electrode. The electrode is preferably tapped, as indicated at 116, for the reception of the terminal screw.

In Figure 8 a modified construction is shown in 15 which the electrode 117 has a serrated cup-shaped surface 118 for contact with the retained body of mercury, the serrations in the surface increasing the contact area between the retained body and the electrode surface to reduce the resistance therebetween. The outwardly extending portion of this electrode is provided with an annular cylindrical extension 119 to which are joined integral ribs 120 which diverge outwardly 20 from the rear face of the electrode 117 in such manner as to provide for reception of a contact terminal screw within the tapped opening 122. These ribs, because of their thin section, act to rapidly dissipate heat from the electrode in the same manner that flanges or fins are provided 25 on cylinder heads or the like for equivalent purposes.

In Figure 9 a rather plain form of electrode is provided, the electrode 125 of this form of the invention having the cup-shaped portion 126 within which the retained body is disposed, and having a cylindrical flange extension 127 which is entirely open or recessed axially to provide access to the tapped opening 128 for receiving the terminal screw. Similarly, the electrode 130 in Figure 10 has a solid cylindrical section 132 extending rearwardly thereof for facilitating heat dissipation, and is provided with the centrally disposed tapped opening 133 for the reception of the terminal screw.

45 It is to be understood that in all embodiments of the invention in place of a single metallic envelope, a bimetallic envelope may be employed using hot rolled strip for the inner lining surface, and having copper or a similar metal enclosing the same to prevent escape of hydrogen if the switch is of the gas-filled type. Also, the ceramic inserts may be provided with "Alundum" portions 50 at the annular contact making and breaking points to prevent breaking down of the insert edge under repeated high temperatures and arcs, as shown clearly in Figure 3 of the drawings.

It is therefore believed that I have provided a 55 novel type of switch construction designed to meet the particular operating requirements of such switches and capable of long, continued rapid operation without any appreciable building up of the operating temperature to a point such as to destroy the life of the switch.

I am aware that various changes may be made 65 in certain of the details of the constructions illustrated and described, and I therefore do not intend to be limited except as defined by the scope and spirit of the appended claims.

70 I claim:

1. A metal envelope mercury switch having an 75 insert in one end carrying an electrode, a hydrogen atmosphere within the envelope, and a movable body of mercury in contact with the envelope, said envelope comprising a ferrous lining

with an external covering of copper impervious to the passage of hydrogen therethrough.

2. A metal envelope for a mercury switch of the metal envelope type, comprising a cup-shaped shell having a lining of ferrous metal and a covering of a metal impervious to hydrogen. 5

3. The envelope of claim 2 wherein said lining comprises 10% or less of the thickness of said envelope.

4. A metal envelope mercury switch comprising 10 an electrode shell open at one end, an insert in said ends, an electrode centered in said insert and having an outwardly projecting shank, a resilient gasket about said shank within said open end of said shell, and a ceramic compression 15 member abutting the outer face of said gasket and having an aperture receiving said electrode shank, said aperture having radial clearance about said shank increasing toward the outer end thereof, said shell having its edge spun radially 20 inwardly to lock said compression member and gasket in position and to impose axial pressure thereon.

5. In a metal envelope mercury switch having a ceramic insert in one end thereof, an electrode 25 centered in said insert and having an axially projecting shank, a resilient gasket about said shank sealing the outer faces of said electrode and insert, a compression member fitting closely in the envelope against the outer face of said gasket 30 and having an outwardly tapered bore receiving said shank, and means for exerting axial compression on said member to compress said gasket into sealing engagement about said shank and against the internal surface of the envelope. 35

6. The combination of claim 5 wherein said compression member has an axial extension about said shank projecting beyond the end of said envelope.

7. In a metal envelope mercury switch, an electrode shell having an enlarged open end, a ceramic insert in said end having an axial bore opening into the closed end of the envelope and a second bore of greater diameter opening outwardly, an electrode having a cup-shaped face 45 centered in said larger bore with the edge thereof seated against the shoulder in the bore, the shank of said electrode extending axially outwardly, a resilient sealing gasket engaging the outer faces of said insert and electrode, and a refractory 50 ceramic compression member engaging the outer radial face of said gasket and having a tapered bore fitting about said electrode.

8. A metal envelope mercury switch comprising a cup-shaped electrode shell having a ceramic 55 insert in the open end thereof, said insert having a frusto-conical recess opening into the shell, a cup-shaped electrode centered in the insert adjacent the small end of said recess, and a ring of a highly refractive ceramic material forming 60 the inner end of said recess, the peripheral edge of said electrode having abutment against both said ring and said insert.

9. The switch of claim 8 wherein said ring 65 material comprises "Alundum."

10. A ceramic insert for a metal envelope mercury switch comprising a body portion having an axial frusto-conical recess extending into one end thereof, a coaxial cylindrical bore extending 70 into the opposite end thereof of a greater diameter than the small end of the recess and overlapping the same to form an annular groove thereabout, the material forming the portion between said groove and recess being more highly refractive 75

and less thermally conductive than the remaining portion of said body portion and being supported on an angle surface of said insert preventing movement thereof toward the outer edge of said recess.

5 11. A metal envelope mercury switch comprising a cup-shaped electrode shell having an enlarged open end, a ceramic insert in said end having a frusto-conical axial recess, a cup-shaped electrode in said insert closing the small end of the recess and having an outwardly projecting

shank of a diameter substantially equal to that of the large end of said recess.

12. The switch of claim 11 wherein said shank is axially recessed and provided with a central terminal post portion.

13. The switch of claim 11 wherein said shank has radially projecting longitudinal fins.

14. The switch of claim 11 wherein said electrode has a serrated surface defining the cup portion thereof.

10 PAUL S. BEAR.
